UNITED STATES PATENT OFFICE

SAMUEL E. SLONIMSKY, OF SAWTELLE, CALIFORNIA

AIRPLANE PROPELLER

Application filed May 21, 1929. Serial No. 364,805.

This invention relates to and has for an object the provision of an improved propeller mechanism adapted for use in connection with airplanes and the like, and provided with means whereby the pilot is enabled to change the pitch of the blades to various angles, or to neutral positions, or to reverse the blades at the will of the pilot while the plane is in the air.

10 My improved propeller is adapted to provide a high factor of safety at the moment of greatest peril to which an airplane may be subjected during flight, and to this end the mounting or installation of the propeller is so arranged as to make it adaptable to any existing type of air craft and motor.

My invention comprehends the provision of a practicable mechanism conveniently arranged so that a pilot may adjust the propeller readily with one hand, the provision of a mechanism of relatively small size and compactness with a low landing speed and embodying means whereby when the landing gear touches the ground the propeller can be reversed so that it will operate as a brake for more quickly stopping the momentum of the plane than is possible with other types of propellers.

Other objects will appear as the description progresses.

In the accompanying drawings I have shown a preferred form of the invention illustrating a multiple blade propeller operatively connected with the propeller shaft of an airplane motor and mounted in the usual position at the front of the fuselage of an airplane. In said drawings:

Fig. 1 is a central longitudinal section of my improved propeller and associated parts mounted on an airplane in position for use.

Fig. 2 is a continuation of Fig. 1 showing the means for adjusting the pitch of the propellers, said means being positioned within and suitably mounted on the fuselage.

Fig. 3 is a horizontal section on line 3—3 of Fig. 2.

Fig. 4 is a transverse section of the propeller mounting on line 4—4 of Fig. 1.

Fig. 5 is a section of the same on line 5—5 of Fig. 1.

Fig. 6 is a transverse section of the control mechanism on line 6—6 of Fig. 2.

Fig. 7 is a section of one of the propeller mountings on line 7—7 of Fig. 1.

Fig. 8 is a transverse section of the control mechanism on line 8—8 of Fig. 1.

Fig. 9 is a sectional plan on line 9—9 of Fig. 1.

Fig. 10 is a section of a master gear adapted to be manually operated for simultaneously adjusting all of the propellers to a corresponding extent and in corresponding directions.

Fig. 11 is a diagrammatic view showing an extension of the hub of the master gear for illustrating the lead and extent of means formed within the hub for effecting and limiting the movement of said gear.

Necessarily I have omitted from the drawings and will not describe herein certain well known parts of an airplane including the motor and fuselage, as they are not material to my invention.

Now referring to Fig. 1, the mechanism is adapted to be mounted on the front of the frame of a motor A and operatively connected with the crank shaft or propeller shaft A1 of the motor. Preferably I provide a mounting for the propellers consisting of a cast metal member C having an elongated hollow extension C1 which is rigidly attached to the extended end of the motor shaft A1 by a bolt or bolts C2, as shown, or as may be found otherwise desirable.

The outer end of the member C is provided with a housing C3, which is open at its end and is adapted to be provided with a detachable cover C4 held in position by means of bolts or screws C5. The housing C3 is provided with a gear chamber C6 therein in which a master beveled gear D is rotatably mounted, said gear having an elongated hub D1 which is journaled in a bore C7 of the hub. Said housing is provided with a plurality of radially formed bosses C8 which rotatably support a corresponding number of beveled pinions D2 in mesh with the master gear D. The pinions D2 have integrally formed shafts D3 which are journaled in and extended outwardly from the bosses C8. The

extended ends of the shafts D3 carry propeller blade mountings E which are tightly held thereon by means of screws or pins E1 extending thru bosses E2.

The housing C is provided with a bore C9 which slidably supports the rear end of a shaft D4, and said shaft extends thru the bore D5 of the gear D and also into an internal boss C10 on the housing cover C4. The boss C10 of cover C4 and the boss D1 of gear D are provided respectively with diametrically opposite longitudinal grooves C11 and D6 which are adapted to be engaged respectively by diametrically positioned pins D7 and D8 carried in the shaft D4, as shown in Fig. 1. Thus the shaft D4 is held against rotation while the master gear D is permitted to rotate substantially on the shaft by reason of the angularity of the grooves D6 formed internally of the hub of said gear. The gear D is fixedly held in the housing C by means of a ring D9 which abuts the inner end of the hub D1 of said gear and is mounted in the bore C7 of the housing. Said ring is held against movement by means of a plurality of screws D10 which are threaded into the portion C1 of housing C, and the inner ends of which extend into the bore C7 and into engagement with the rear side of the ring D9. This means constitutes a simple expedient for preventing the longitudinal movement of the gear D, but it will be understood I may resort to any other suitable means in lieu of the means shown.

The portion C1 of the housing C is provided with a pair of diametrically opposite grooves C12 which are adapted to be engaged by plates D11 carried in the inner end of the shaft D4 and held by means of a screw D12, the head of which is seated in a bore D13 of said shaft.

A frictionless ball bearing F is slidably held on the portion C1 of the housing and includes an inner rotatable collar F1 which is engaged by the key plates D11. An outer non-rotatable collar F2 between which and the collar F1, balls F3 are suitably held and a housing F4 embracing said collars and said balls. The bearing F also includes a retainer ring F5 which is threaded into the housing F4 for holding the elements of the bearing in operative position.

It will be observed that the inner ends of the bosses E2 of the propeller mountings E are each provided with a plurality of notches E3, E3, etc., adapted to be engaged by arms E4 radiating from a collar E5 which is adjustably mounted on the outer periphery of the portion C1 of gear housing C. Housing C is provided at each of the hubs C8 thereon with a pair of spaced ribs C13 which provide grooves C14 therebetween for registration with selected notches E3 on the members E. The ribs C13, as shown in Fig. 1, are sufficiently wide and the grooves therebetween

sufficiently deep as to receive and hold the portions E4 of the collar E5 against displacement when said portions E4 are adjusted out of engagement with the notches E3.

The collar E5 is provided with an annular groove E6 adapted to be engaged by a portion G1 of a member G, which is slidably mounted on a bracket G2 and is adapted to be operated by means hereinafter described for disengaging the collar E5 from the grooves E3 of the propeller mounting so as to permit the adjustment of the propellers.

The bracket G2 is adapted to be secured to the motor block A by suitable means such as bolts G3 and is provided with a pair of spaced ribs G4 between which a bell crank G5 is pivotally mounted on a shaft G6. The member G is longitudinally slidable in a guideway comprising grooves G7 formed in the lower portions of the ribs G4 and a web G8 underlying the member G. The bell crank G5 has a depending arm G9 which extends thru an aperture G10 in the member G and also thru an elongated slot G11 in the web G8. Said bell crank is also provided with a pair of oppositely extended arms G12 which are respectively connected with the ends of cables G13 and G14 at points remote from the axis of the bell crank.

Inwardly of the motor A a suitable portion of the fuselage H is provided with a bracket G15 which carries an operating wheel G16 on a vertical shaft G17 which is held in spaced bearings G18 and G19. Said bearings are formed on a fixture G20 which has an externally threaded hub G21 adjustably associated with a similar hub G22 on the bracket G15. The hubs G21 and G22 are adjustably connected by means of a set collar G23, which has its opposite ends reversely threaded while the hubs are correspondingly threaded so that the adjustment of the set collar on the hubs will adjust the fixture G20 in its position relative to the bracket G15.

The collar G23 may be provided with a set screw G24 by means of which the collar may be set when a proper positioning of the fixture G20 on the bracket is accomplished.

Intermediate the bearings G18 and G19 the shaft G17 has fixed to it a pulley G25 over which the cables G13 and G14 are adapted to be wound for oscillating the bell crank G5 when the hand wheel G16 is turned. Said cables G13 and G14 extend thru a tube G26 leading from the motor block A thru the fuselage H to the interior of the hubs G21 and G22.

The hand wheel G16 is locked in selected positions by means of a latch G27 which is pivotally mounted on the bracket G15 at G28 and has an end G29 adapted to engage selected slots G30 formed at intervals in the web of the wheel G16. The bracket G2 carries at one side of it a pulley G31 which is mounted on a shaft G32 journaled in suitable

bearings on said bracket, and a cable G33 operates over said pulley and thru the tube G26 and bosses G21 and G22 while the ends of said cable are connected at diametrically opposite points to portions G34, G34 of a lever G35 which is pivotally mounted on the shaft G17 of the hand wheel G16. Said lever is adjustably mounted relative to a quadrant G36 and is bifurcated at G37 to provide a mounting for a latch G38 between the furcations thereof. The latch G38 is pivotally held on a pin G39 and has a finger piece G40 and a depending portion G41 which is adapted to engage selected apertures G42 in the quadrant G36. Obviously the movement of the lever G35 in a given direction will effect a corresponding movement of the pulley G31 and cable G33. The purpose of the mechanism including the lever G35 and pulley G31 is to reciprocate the shaft D4 within the housing C. This movement of said shaft is effected by means of a yoke G43, as shown in Fig. 5, which is pivotally mounted on the shaft G32 of the pulley G31 and is provided with slots G44 in its depending ends for engagement with trunnions F8 diametrically formed on the housing F4 of bearing F. Thus the movement of pulley G31 in a counter-clockwise direction which will effect the retraction of shaft D4 in the housing C and a corresponding rotary movement of the master gear D and pinions D2 together with the propellers. In order to accomplish this movement of the propellers, however, it is first necessary to unlatch the hand wheel G16, after which said wheel may be rotated in a given direction for oscillating the bell crank G5 with which the bell crank is connected by means of the cables G13 and G14.

The movement of the bell crank in a counter-clockwise direction as seen in Fig. 1 will slide the member G and the collar E5 with which said member is connected to the left, thus disengaging the portions E4 of said collar from the notches E3 of the propeller mounting.

Following this operation the lever G35 is operated as previously described for adjusting the pitch of the propellers.

The propeller blades I may be suitably mounted within the sockets E7 of the members E by bolts or otherwise so that they may be readily detached therefrom or permanently held therein as may be desired. When the propellers I are adjusted to a desired pitch the hand wheel G16 is reversely operated for restoring the collar E5 into engagement with the notches E3 of the propeller mountings whereby the propellers will be locked in adjusted positions, and thereafter the latches G27 and G38 are also operated for locking the wheel G16 and lever G35.

The member C carries a spring E8 between the collar E5 and a ring E9 which urges the

collar into locking position with the propeller mountings, said ring being engaged by the outer portions of the screws D10 for compressing the spring.

The pitch and length of the grooves D6 in the master gear D determine and regulate the extent of movement of the propellers I. It is only required, however, that the propellers be adjusted for a maximum extent so that they may be reversed as to pitch for imparting a braking influence to the mechanism instead of a propelling influence.

An important feature of my mechanism consists in the means provided for adjusting the propeller blades forward or reverse to any desired extent substantially within the range of 180 degrees for varying the air resistance and the propelling power. Such a mechanism is especially valuable as when, for instance, a plane becomes over balanced and in its descent is inclined nose downward in the direction of the ground and out of control of the pilot, the propellers may be quickly adjusted by the pilot into reverse for imparting an air resistance to the descent of the plane which tends to place the plane in balance, elevate the nose, and lower the tail of the plane until equilibrium is established.

Likewise, in the event that the plane should be reversely over balanced with the tail lowermost, the propellers may be adjusted to a greater angle for increasing the propulsion effort and for correspondingly elevating the tail until equilibrium is established.

In aircrafts employing a plurality of motors, the different sets of propellers may be differently adjusted to compensate for the greater or less efficiency of one or some of the motors relative to the others. In the event one of the motors of such a plane should become useless the propeller blades on such motor may be adjusted into neutral position with their edges facing forward, thus providing a minimum air resistance to the flight of a craft.

My mechanism being entirely mechanical has distinct advantages over other types of propeller adjustments employing electrical means, for the reason that mechanical means are more certain and dependable.

Other advantages will readily appear to those skilled in the art.

What I claim is:

1. An airplane propeller comprising, in combination with a driving shaft, a hub fixed on said shaft, a plurality of propeller shafts journaled in said hub, pinions secured on the inner ends of said propeller shafts, propeller blades secured on the outer ends of said propeller shafts, a gear in mesh with said pinions and formed with a hub journaled in said driving shaft, said gear hub being formed with a spiral internal groove, a slide shaft extending through said hub, means to prevent turning of said slide shaft with relation to said

- drive shaft, a pin in said slide shaft engaging the groove in said gear hub, a lock for normally locking said propeller blades against turning, means for disengaging said lock from said propeller blades, and means for moving said slide shaft longitudinally when said lock is disengaged as aforesaid, for turning said propeller blades through said pin, groove, gear, pinions, and propeller shafts.
- 10 2. An airplane propeller mechanism comprising a propeller housing, a plurality of propeller blades radially mounted thereon and adjustable as to pitch, a driving shaft rotatable in said housing, means adjustable 15 relative to said shaft for varying the pitch of said blades at will, hubs on said blades having locking recesses formed at corresponding points thereon, and a member slideable relative to said housing and having portions engaging the recesses in said blade hubs for locking the blades in adjusted positions.
- 20 3. An airplane propeller mechanism as characterized in claim 2, including manually operable means for retracting said locking 25 member whereby to disengage the same from said blade, and means for restoring said locking member to locking engagement with the blades at the completion of a blade adjusting operation.
